UNITED STATES PATENT OFFICE.

LOUIS KESSLER, OF CHICAGO, ILLINOIS.

PUMP-METER.

1,148,095.

Specification of Letters Patent. Patented July 27, 1915.

Application filed September 24, 1914. Serial No. 363,263.

To all whom it may concern:

Be it known that I, LOUIS KESSLER, a citizen of the United States, residing at Chicago, in the county of Cook and State of Illinois, have invented a new and useful Improvement in Pump-Meters, of which the following is a specification.

The object of my invention is to so combine with a rotary pump a meter as to cause the latter to be turned, for registering, in one and the same direction, in whichever direction the pump is being turned, whether for withdrawing liquid from a supply thereof or introducing it into a holder.

I have more especially devised my improvement for use with pumps on garage-tanks holding gasolene, and therefore describe it hereinafter in that particular connection and also illustrate it therein in the accompanying drawings, though not intending to limit it to that use.

In the drawings, Figure 1 is a broken view in elevation showing the top-portion of a gasolene tank provided with a pump equipped with my improvement: Fig. 2 is a face view of the pump and meter; Fig. 3 is an enlarged view showing the meter mechanism in rear elevation; Fig. 4 is a section on line 4, Fig. 3; Fig. 5 is a section through the pump on line 5—5, Fig. 6, and Fig. 6 is a section on the irregular line 6—6, Fig. 5.

On the top of a gasolene-tank 7, near one end, is shown a capped filling tube 7^a (Fig. 1) and near the opposite end a hollow post 8 containing a tube 9 dipping into the tank and having coupled with it a neck 10, in the upper end of which is seated a check valve 11. A cam-like head 12, in the inner end of a stem reciprocably supported in a stuffing box 13 on a side of the neck, is in position to engage the lower end of the valve-stem for raising and holding it from its seat, for the purpose hereinafter explained.

The pump comprises a chamber in the form of two contiguous circles each having journaled and fitting in it a rotatable pumping member comprising a toothed wheel 14, the teeth of the two wheels intermeshing through the opening between the two circular chamber-sections to cause the turning of one, as by a crank-handle 15 on the projecting end of its shaft 16, to turn the other and, by turning the handle in one direction, pump gasolene out of the tank, and by turning the handle in the opposite direction pump gaso-

lene into the tank. A valved pipe 17 centrally on the top of the pump-casing has a hose 18 attached to its distal end and may serve as a suction or discharge pipe, depending on the direction of operating the pump. 60

The pump-construction thus described presents no novelty.

On the front head of the pump-chamber is supported, by rods extending forwardly therefrom and one of which is shown at 19 in Fig. 1, a casing 20 open at its front side, relatively large and circular toward one end and tapering toward the opposite end. The shaft 16 extends through a sleeve 16^a projecting from and formed integral with the forward pump-chamber head and passes transversely through the narrower section of the casing 20, the open side of which is closed by a face-plate 20^a fitting and secured against it, and beyond which the shaft carries the handle 15. On the section of this shaft within the casing 20 is secured to rotate with it an eccentric circular head 21, into the periphery of which is let an annular strap 22 loosely surrounding the head and confined thereon by a circular face-plate 23. An arm-like pawl 22^a extends rigidly from the periphery of the strap and has pivotally hung upon it, near its outer end, a weight 22^b. In the larger section of the casing 20 is concentrically journaled a ratchet-wheel 24, against which the pawl acts. On the forward end of the ratchet-shaft is mounted, to rotate with it, a dial 25 covering the expanding section of the casing 20 and against the face of which bears a spring-brake 26 secured on the outer end of the shaft. The dial-face is marked off with indications 27 suitably spaced about the dial to denote gallons to the number of five, being numbered from 1 to 5, with intermediate indications denoting fractions of gallons. A stationary index-finger 28 extends from the top of the casing 20 over the edge of the dial. 35 70 75 80 85 90 95 100 105 110

By turning the handle 15, say in clockwise direction, each rotation of the eccentric head 21 reciprocates the pawl, whereby in the advance movement of the latter it turns the ratchet the extent of one tooth and with it the dial, and is then retracted to engage the next ratchet-tooth, the pawl being held yieldingly against the periphery of the ratchet by the weight 22^b. Obviously, by turning the handle in the contrary direction the ratchet and dial thereon are still ro-

tated in the same direction as by turning the handle in the clockwise direction.

In the construction shown, the wheel 24 has forty-five teeth, and the arrangement of the parts is such as to require the eccentric head 21 to make nine complete revolutions, thereby actuating the ratchet nine times to cause the pump to pump one gallon of gasoline into or out of the tank and to turn the dial the distance from one indication 27 to the next; so that a person observing the dial while the pump is being operated may readily read thereon, with the aid of the index-finger, the number of gallons and fractions of a gallon being pumped. Of course, this particular arrangement for actuating the dial may be varied to suit different purposes. For pumping the liquid into the tank, from any suitable source, the handle 15 is turned in the counter-clockwise direction, but preparatory to so turning it the cam-head 12 must be moved inwardly to raise and hold the valve 11 off its seat while the pump is being thus operated.

I realize that considerable variation is possible in the details of construction of my improved meter-device thus specifically shown and described, and I do not intend by illustrating a single specific or preferred embodiment of my invention to be limited to such details; my intention being in the following claims to claim protection upon all the novelty there may be in my invention as broadly as the state of the art will permit.

What I claim as new and desire to secure by Letters Patent is—

1. In combination with a rotary pump having a pumping member rotatable in relatively opposite directions, a meter comprising a dial supported to turn axially, and means connecting said member and dial and operating to turn the dial only in one and

the same direction by turning said member in either direction.

2. In combination with a rotary pump 45 having a pumping member rotatable in relatively opposite directions, a meter comprising a dial supported to turn axially, and pawl and ratchet mechanism connecting said member and dial and operating to turn the 50 dial only in one and the same direction by turning said member in either direction.

3. In combination with a rotary pump having a pumping member rotatable in relatively opposite directions, a meter comprising a rotatably supported ratchet, a dial secured on the ratchet-shaft, an eccentric on the shaft of said member, and a pawl extending from the eccentric into engagement with the ratchet-teeth.

4. In combination with a rotary pump having a pumping member rotatable in relatively opposite directions, a meter comprising a casing on the pump, a ratchet journaled in the casing, a dial secured on the ratchet-shaft, an eccentric in the casing on the shaft of said member, and a weighted pawl extending from the eccentric into engagement with the ratchet-teeth.

5. In combination with a rotary pump having a pumping member rotatable in relatively opposite directions, a meter comprising a casing on the pump, a ratchet journaled in the casing, a dial secured on the ratchet-shaft, an index-finger extending over the dial-face, an eccentric head on the shaft of said member in the casing, a strap loosely confined about said head, and a weighted pawl extending from said strap into engagement with the ratchet-teeth.

LOUIS KESSLER.
